DECELERATION APPARATUS

Filed Aug. 15, 1946

UNITED STATES PATENT OFFICE

2,498,045

DECCELERATION APPARATUS

Charles T. G. Looney, Silver Spring, Md., Lynn G. Howell, Houston, Tex., and Bruce G. Johnston, Bethlehem, Pa., assignors to the United States of America as represented by the Secretary of the Navy

Application August 15, 1946, Serial No. 690,768

11 Claims. (Cl. 73—167)

1

This invention relates generally to deceleration apparatus and is particularly directed to improvements in apparatus for the deceleration of projectiles.

Ruggedness tests of vacuum tubes and other components constituting the proximity fuze are presently made by the vertical method, whereby the materials being tested are contained in a projectile and fired directly upwardly and permitted to fall base downwardly in a field within the vicinity of the gun where the projectile is recovered by digging it out of its embedded location. This method requires a large plot of ground in a secluded area far from inhabited areas due to the frequent occurrence of wild or improperly fired projectiles. A large group of men are required to operate the gun, observe the landing of each projectile, and dig the projectile out of the ground; all of which duties are performed by the men under the dangerous condition of being struck by a falling projectile. A great deal of time is consumed since the materials being tested have to be shipped to and from the laboratory and the testing grounds. Also, damage to the materials within the projectile may occur on landing, which situation gives rise to the necessity of repeated tests in order to arrive at an accurate conclusion since it would not be known if any of the damage was caused on firing the projectile.

The present invention provides an improved ruggedness test apparatus wherein the projectile containing the materials being tested is fired horizontally and decelerated after a relatively short distance or travel by a fluid under pressure. The apparatus is sufficiently compact to be housed in a small space within the vicinity of the laboratory or factory. The test itself is positive in result without requiring unnecessary duplication of effort and does not subject the operators, who are few in number, to any dangers that are prevalent in the vertical recovery method.

The principal object of the present invention is to provide a projectile deceleration apparatus which is compact and simple in construction and efficient in operation.

Another object of the present invention is to provide apparatus for decelerating projectiles which may be operated by very few men without subjecting the operators to any of the dangers that are prevalent in the present testing methods.

A further object of the present invention is to provide apparatus that permits a greater rapidity of ruggedness tests.

A still further object resides in the provision of

2

a projectile decelerating apparatus which employs fluid under pressure for retarding the fired projectiles within a short distance from the point of fire.

5 These and other objects of the invention will be evident from the following specification and the accompanying drawings, in which:

Figure 1 is a diagrammatic view partly in section of the projectile decelerating apparatus.

10 Figure 2 is a side sectional view in elevation of the gate apparatus.

Figure 3 is a sectional view in elevation of the pressure operated switch.

15 Referring now to the drawings the numeral 10 indicates a fragment of the muzzle end of the barrel of a gun whose axis is in direct alignment with that of a deceleration pipe 12 which is of substantial length and mounted parallel to the ground of a desired height there above by suitable standards (not shown). The gun barrel 10 and the deceleration pipe 12 may be aligned by means of a transit or by any other of the well-known methods, but once aligned only occasional checking of alignment is necessary. The barrel 20 10 is spaced from the pipe 12 to provide a gap permitting the muzzle gases to escape to the atmosphere, the gap increasing in size as the gun recoils. The muzzle end of the barrel 10 is clamped to its mounting (not shown) by a steel collar 10a 25 which holds the gun barrel 10 in alignment but permits the barrel to recoil upon firing. Likewise, a plurality of clamps (not shown) retain the deceleration pipe 12 in position.

30 35 A horizontally hinged gate 11 shown in detail by Figure 2 is mounted in the gap between the barrel 10 and the pipe 12. The purpose of the gate 11 is to block off the passageway at the gap after the projectile has been fired so that the muzzle of the barrel 10 will not be injured by a 40 projectile that may be blown backward by pressure in the pipe 12, as is hereinafter described in detail.

35 45 The gate 11 consists of a base plate member 40 on each side of which is welded or otherwise secured a respective pair of upright supports 41 and 42. A gate member 43 is swingably mounted on the upright support 41, 41 by means of a pin 44 extending through bores in the supports. Bolted to the upper end of the gate member 43 50 55 there is an L-shaped arm 45 at the free end of which an extension arm 47 is hinged by a pin 46. An adjustable bolt 48 is threaded through the extension arm 47 to normally rest on the end of the gun barrel 10. A guide rack consists of two parallel bars 49 between and along which the

free end of the gate member 43 swings, the bars 49 being secured at their base portions to the upright supports 42, 42 and at their top portions by a cross bar 50. At the pivoted end of the gate member 43 there is a contact making switch member 51. An electric switch 52 is mounted on the base plate member 40 and positioned adjacent to the contact making switch member 51 so that with the gate member 43 in its upper position the firing circuit is closed while with the gate member 43 in its lowered position the firing circuit is opened. The switch 52 is connected by wires 32a, 32b in series with a firing circuit hereinafter described in detail.

When the gun is fired, its recoil while increasing the gap will permit the bolt 48 to slip past the end of the barrel 10 and swing downwardly causing the gate member 43 to fall to its lower position thus blocking off the open end of the pipe 12. In the event the projectile, which has been decelerated in the pipe 12, is blown back through the pipe 12 by the fluid pressure therein, the gate member 43 will arrest the movement of the projectile at the gap and prevent injury to the gun barrel 10. When the gun recovers from its recoil, and returns to the position shown in Fig. 1, the gate 43 still will be in front of its muzzle, shielding it from the projectile that might be returning from the pipe 12. It will be seen that the extension arm 47 at this time will be well below the bottom of the gun barrel and will not be struck by said barrel after recoil. Before the next firing, the arm 47 and associated parts are readjusted manually.

A relatively large cylindrical projectile receiving chamber 13 is provided with a reduced inlet pipe 14 which is secured to and on the same axis with the rearward end of the decelerating pipe 12 by a T-coupling 15. The chamber 13 may contain a cushioning material (not shown) such as cotton and the like for stopping the projectile without injury to the equipment in those instances when the fluid pressure in the pipe 12 fails to completely decelerate the projectile.

An air storage tank 16 connected to an air compressor (not shown) of conventional design has a valve chamber 17 in which a valve 18 is mounted. A pipe 19 connects the valve chamber 17 to the T-coupling 15 to permit air under pressure in the storage tank 16 to flow into the decelerating pipe 12 when the valve 18 is opened. The valve 18 is operated by an auxiliary valve mechanism 20 which includes a cylinder 21 and a piston 22 slidably mounted therein carrying the valve 18 at one end and a contact stem 23 at the other end thereof. The contact stem 23 carries at its outer end a contact sleeve 28 and an insulating sleeve 29. A contact arm 30 is mounted for engagement with either the contact sleeve 28 or the insulating sleeve 29 depending on whether the valve 18 is opened or closed respectively.

Air for shifting the piston 22 in the cylinder 21 is supplied from the tank 16 through a pipe 24 and a two-way valve 25 operated by a solenoid 26 connected to a suitable current source 27. An operating lever 25a for operating the valve 25 is connected to the free end of an armature 26a so that when the solenoid 26 is energized, the valve 25 is shifted in one position to permit flow of air under pressure into one side of the cylinder 21 and discharge of air out of the other side causing the piston to shift. When the solenoid 26 is de-energized the valve 25 is shifted to its second position and the flow of air is reversed causing the

piston to shift in an opposite direction. A starting switch 27a is connected between the solenoid 26 and the current source 27 to control the operation of the valve mechanism 20.

An electrical delay apparatus 31, which is well-known in the art, has a pair of input or control terminals 32, one of which is grounded at the cylinder 21 while the other is connected to the contact arm 30. A pair of electric conductors 32a connects the output of the electric delay apparatus 31 with the gun control apparatus (not shown) such as firing solenoid, having the switch 52 connected in series with one of the electric conductors 32a so that the firing circuit is closed only when the gate member 43 is in upper or non-obstructing position.

A pressure operated switch 33 is mounted on the deceleration pipe 12 at its receiving and adjacent the gap between the pipe 12 and the gun barrel 10. As shown in detail by Figure 3, the switch 33 consists of a mounting 34 made of a non-conducting material such as a synthetic resin or the like, having a vent passage 35 extending through the mounting 34 and connecting the atmosphere with an air chamber 36 situated on the forward face of the switch 33. A flexible diaphragm 37 which is mounted on the forward face of the switch 33 by screws 39 carries a contact member 38 maintained normally in spaced relationship to an electrical connector 53 threaded through the mounting 34. A second electrical connector 54 is threaded through the mounting 34 making contact with the flexible diaphragm 37 at its periphery. Electric conductors 55, 55 connected to the connectors 53 and 54 extend to a second conventional electrical delay apparatus 56, one of the conductors 55 having an electric power source 55a interposed therein. On the output side of the delay apparatus 56, an electric conductor 57 extends to the pipe 12 where it is grounded, and a second electric conductor 58 extends to a conventional circuit breaker 59 and an electrically operated relief valve 60 which are connected in parallel. The relief valve 60 is of the catch retained type which is released by operation of the solenoid and upon a drop in fluid pressure caused by the opening of the valve 60, the valve returns to its closed position.

A plurality of electrodes 61 are positioned at fixed distances apart on the deceleration pipe 12 along its full length. The function of the electrodes 61 is to pick up the change in magnetic field caused by the passage of the projectile and to convey this change to a magnetic flux indicator 62, connected by conductors 63 to the electrodes 61, and having a suitable source of electricity 64 connected thereto. An oscilloscope or other appropriate electrical indicating device 68 is connected to the output leads 65 of the magnetic flux indicator 62, as shown. By this method, the deceleration rate of the projectiles can be computed and the proper air pressure for a desired rate of deceleration can be obtained accurately. The timing of the passage of the projectiles past the spaced stations along the pipe 12 can be done by any of the well-known methods such as using photo-electric cells, change in pressure indicators or electric contact makers.

In the normal operation of the deceleration apparatus upon closing the starting switch 27a, the solenoid 26 becomes energized and the valve 25 is turned thereby to the position shown by Figure 1 permitting air under pressure to flow from the storage tank 16 through the valve 25 and into

the cylinder 21, thus forcing the piston 22 to shift carrying the main valve 18 to its opened position. Air under pressure then flows past the main valve 18, through the coupling 19 and into the deceleration pipe 12. The stem 23 secured to the piston 22 likewise shifts carrying the contact sleeve 28 into engagement with the contact arm 30 for setting the electrical delay apparatus 31 into operation. After a delay of predetermined time, sufficient to permit the deceleration pipe 12 to become filled with air under considerable pressure, the electrical delay apparatus causes the gun to be fired. Upon recoil of the gun, at which time the projectile has entered the deceleration tube 12, the bolt 48 on the extension arm 47 of the gate 11 slips past the end of the barrel 10, allowing the gate member 43 to swing downwardly into its obstructing position between the gun barrel 10 and the receiving end of the deceleration tube 12. The expanding gases, produced by the firing of the projectile, escape to the atmosphere at the gap between the barrel 10 and the deceleration pipe 12, and actuate the flexible diaphragm 37 causing the make contact with member 38 to contact the connector 53 thereby closing the circuit to the electrical delay apparatus 56. As the projectile passes the stations at which the electrodes 61 are positioned on the pipe 12, each of the electrodes 61 conveys to the indicators the moment of its passage whereby the deceleration rate may be computed and the proper air pressure for decelerating the projectile can be obtained.

Before the projectile has travelled a substantial distance through the pipe 12, the electrical delay apparatus 56 operates to cause the air pressure relief valve 60 to open and the circuit breaker 59 to open the circuit connected to the solenoid 26 resulting in the closing of the main valve 18. Upon the release of pressure in the deceleration pipe 12, the relief valve automatically closes, and the projectile which has been decelerated is now removed from the pipe 12 by blowing the projectile back through the pipe 12 to the gate member 43 at the open end of the deceleration pipe 12 by use of air pressure. If the projectile travelled through the full length of the pipe 12 and was stopped in the chamber 13, the projectile is removed by opening a gate (not shown) in the chamber 13. The projectile on being removed from the apparatus is then sent to the laboratory for observation and analysis. In order to repeat the projectile deceleration test, the main switch 27a is opened, the circuit opened by the circuit breaker 59 is closed, and the gate member 43 is swung to its upper or non-obstructing position so as to permit a clear passage to the projectile to be fired, and the firing circuit 32a is closed by the switch 52.

While the form of the device herein shown and described constitutes the preferred form of embodiment of the present invention, it is to be understood that other forms might be adopted all coming within the scope of the claims which follow.

What we claim is:

1. A device for decelerating projectiles fired from a gun, comprising a tube closed at one end and open at the other end, and a source of compressed fluid connected to the tube near its closed end, whereby a projectile fired into the open end of the tube is decelerated by the compressed fluid in said tube, and means actuated by recoil of the gun for preventing return of the projectile to the gun.

2. A device for decelerating projectiles fired from a gun, comprising a tube closed at one end and open at the other end, a source of compressed fluid connected to the tube near its closed end, and time delay means for use in firing the gun after a predetermined time interval following admission of the compressed fluid into the tube, whereby the projectile is fired from the gun into the open end of the tube only after the pressure in the tube has reached a predetermined value, the projectile being decelerated by said compressed fluid.

3. A device for decelerating projectiles fired from a gun, comprising a tube closed at one end and open at the other end, a source of compressed fluid connected to the tube near its closed end, a valve between said source and said tube, a delay mechanism for firing a gun after a predetermined time interval and means for simultaneously opening said valve and actuating said delay mechanism, whereby the projectile is fired from the gun into the open end of the tube after a time interval whereby the pressure in the tube has reached a predetermined value, the projectile being decelerated by said compressed fluid.

4. A device for decelerating projectiles fired from a gun, comprising a tube closed at one end and open at the other end, a source of compressed fluid connected to the tube near its closed end, a valve between said source and said tube, a delay mechanism for firing a gun after a predetermined time interval following actuation of said delay mechanism, a switch for actuating said delay mechanism, a fluid operated piston controlling said valve and said switch, and whereby said piston simultaneously operates said valve and said switch to admit compressed fluid into said tube and to initiate action of said delay mechanism whereby said projectile fired from the gun into the open end of said tube is decelerated by the compressed fluid.

5. A device for decelerating projectiles fired from a gun, comprising a tube closed at one end and open at the other end, a source of compressed fluid connected to the tube near its closed end, a valve between said source and said tube, a delay mechanism for firing a gun after a predetermined time interval following actuation of said delay mechanism, a switch for actuating said delay mechanism, a fluid operated piston controlling said valve and said switch, and a solenoid operated valve for controlling said piston, whereby said piston simultaneously operates said valve and said switch to admit compressed fluid into said tube and to initiate action of said delay mechanism whereby the projectile fired from the gun into the open end of the tube is decelerated by the compressed fluid.

6. A device for decelerating projectiles fired from a gun, comprising a tube open at one end, an enlarged projectile receiving chamber attached to the other end of the tube, means for maintaining the gun muzzle in close spaced relation to the open end of the tube and axially aligned therewith, a source of fluid under pressure connected to said tube near said projectile receiving chamber, a valve between said source and the tube, electrical delay means for firing the gun after the lapse of a predetermined period of time following opening of said valve, and spaced electrical means for indicating the passage of the projectile in the tube for providing data for computing the correct air pressure in the tube to decelerate a projectile sufficiently that it comes to rest in said chamber 75 undamaged.

7. A device for decelerating projectiles fired from a gun comprising a tube open at one end, and having a projectile receiving chamber attached to the other end, means for maintaining the barrel of said gun in spaced relation to the open end of said tube and in axial alignment therewith; means connecting a source of fluid under pressure to said tube adjacent said projectile receiving chamber; a main valve mounted in said last mentioned means, valve operating means, means for actuating said main valve to its open position, an electrical delay means for firing said gun, means operatively connected to said valve operating means for energizing said electrical delay means upon operation of said valve, pressure responsive switch means mounted on said tube adjacent the open end thereof, a second electrical delay means connected to said switch means, a pressure relief valve mounted in said pipe adjacent said chamber, means connecting said last named electrical delay means to said relief valve adapted to open said valve, and further means connecting said second electrical delay means to said switch means for returning said main valve to its closed position.

8. A device for decelerating projectiles fired from a gun comprising a tube open at one end, and having a projectile receiving chamber attached to the other end, means for maintaining the barrel of said gun in spaced relation to the open end of said tube and in axial alignment therewith; means connecting a source of fluid under pressure to said tube adjacent said projectile receiving chamber, a main valve mounted in said last mentioned means, valve operating means, means for actuating said main valve to its open position, an electrical delay means for firing said gun, means operatively connected to said valve operating means for energizing an electrical delay means upon operation of said valve, pressure responsive switch means mounted on said tube adjacent the open end thereof, a second electrical delay means connected to said switch means, a pressure relief valve mounted in said pipe adjacent said chamber, means connecting said last named electrical delay means to said relief valve adapted to open said valve, and further means connecting said second electrical delay means to said switch means for returning said main valve to its closed position, and a gate means mounted in

the space between said barrel and said tube positioned normally out of the path of the fired projectile adapted upon recoil of the gun to become positioned in said path.

5 9. A device for decelerating projectiles fired from a gun, comprising a tube closed at one end, and a source of compressed fluid connected to the tube near its closed end, whereby a projectile fired into the open end of the tube is decelerated by the compressed fluid in said tube, means for protecting the gun from injury by a returning projectile, including a gate biased to close the said open end of the tube, and means mechanically connected with the gate and having a portion in contact with the gun and preventing movement of the gate, but freed from such contact upon recoil of the gun and thereupon in turn freeing the gate to close said open end of the tube.

10 10. A device for decelerating projectiles fired from a gun, comprising a tube closed at one end and open at the other end, said open end facing the muzzle of the gun to receive the said projectiles, a source of compressed fluid for decelerating the projectiles, a conduit for conveying said fluid to the tube, electrically actuated means controlling the flow of the fluid through said conduit, a pressure responsive electrical switch adjacent the muzzle of the gun and operative to control the circuit to said electrically actuated flow control, 25 means to admit the fluid to the pipe when subjected to the pressure of the combustion gases escaping from said muzzle upon firing the gun.

30 11. A device as defined in claim 10, wherein the electrical switch comprises a diaphragm carrying a relatively movable contact in cooperation with an adjustable relatively stationary contact.
